TUNABLE SQUIRREL CAGE MAGNETRON

Milton D. Hare, Chicago, Ill., and Virginia Leonard, Arlington, Mass., assignors to the United States of America as represented by the Secretary of War

Application March 29, 1946, Serial No. 657,944

7 Claims. (Cl. 315—40)

1

This invention relates to electrical apparatus and more particularly to tunable magnetrons.

One type of tunable magnetron radio frequency oscillator is the so called "squirrel cage" magnetron. The squirrel cage magnetron is generally constructed as a substantially cylindrical cavity resonator within which is placed an axially aligned cathode structure. Cylindrically arranged about this cathode and within the cavity resonator is a ring of interleaving anode fingers. Adjacent fingers in this ring are connected at one end thereof to one of two opposite annular anode halves, the anode halves in turn being connected to the opposite end closures of the cavity resonator. A magnetic field is maintained parallel to the magnetron axis by means of two magnetic pole pieces. The anode halves may be provided with water cooling coils to assist in heat dissipation. The term "squirrel cage" is derived from the appearance of the cylindrical ring formed by the two sets of interleaving anode fingers. Tuning of the magnetron is effected by making at least one of the cavity resonator end closures flexible so that it may be moved with respect to the opposite end closure. This relative motion results in a relative axial motion of the interleaving anode fingers with respect to each other thereby varying the frequency of the magnetron.

The present invention is concerned primarily with the standardization and simplification of the manufacturing procedure for squirrel cage magnetrons. Formerly the construction was comparatively difficult because of the many close machining tolerances, the necessity for careful alignment of the various magnetron components and the difficulty of maintaining the alignment during the soldering processing. It is desirable to reduce the number of close tolerances in the machining, to allow the magnetron components to be drawn from sheet stock as far as possible, to simplify the alignment of the magnetron components and to simplify the assembly and soldering of the magnetron.

Accordingly an object of the present invention is to simplify the assembly and the construction of squirrel cage magnetrons.

A further object of the present invention is to decrease the expense of manufacture by utilizing die stamping processes instead of machining processes wherever possible.

A still further object of the present invention is to provide jigs for simplifying the attainment and maintenance of the critical alignment of the magnetron components in the assembly process.

2

Other objects and advantages of the invention will be apparent during the course of the following description.

In essence the manufacturing process and the principal magnetron components may be described by the four subassemblies which are the anode-cavity assembly, the cathode-pole piece assembly, the output loop assembly and the final assembly in which the other two assemblies are joined to the anode-cavity assembly.

In the anode-cavity assembly two jigs are used; the upper jig holds the tuner yoke, the upper magnetic pole piece and the upper annular anode half in axial alignment, while the lower jig holds the cavity resonator shell and lower annular anode half in axial alignment. The lower jig also holds the upper and lower annular anode halves in axial alignment with each other thereby aligning the upper and lower components. The anode cooling coils are held in place by grooves on the outer circumference of the annular anode halves. In addition to the two above-mentioned jigs, there is a spacing jig which is inserted through the output hole in the cavity resonator to secure uniform spacing of the anode fingers.

The cathode-pole piece assembly is assembled separately using the cathode, coaxial heater lead and the lower magnetic pole piece.

The output loop assembly is likewise assembled separately.

Both the cavity-anode assembly and the final assembly are made by soldering in a hydrogen atmosphere.

In the accompanying drawings forming a part of this specification,

Fig. 1 is an isometric view of a squirrel cage magnetron construction which illustrates one embodiment of the present invention.

Fig. 2A is a cross sectional view drawn to a slightly enlarged scale of the output loop assembly of the magnetron of Fig. 1.

Fig. 2B is a partially cross sectioned view drawn to an enlarged scale through the axis of the magnetron of Fig. 1.

Fig. 3 is an isometric view drawn to a slightly reduced scale of the jigs and magnetron components used in the cavity-anode assembly of the magnetron of Fig. 1.

Fig. 4A is an isometric view of the components of Fig. 3 assembled preparatory to soldering.

Fig. 4B is an illustrative view taken at the level of the output hole 63 of Fig. 4A showing the application of the anode finger spacing jig.

Fig. 5 is a cross sectional view drawn to an en-

larged scale through the axis of the cavity-anode assembly of Fig. 4A, showing the disposition of the solder and

Fig. 6 illustrates one method of disposing a heating wire around the cavity-anode assembly of Fig. 4A preparatory to soldering the cavity-anode assembly.

In Fig. 1 the squirrel cage magnetron is pictured in an inverted position with its base uppermost. The remaining figures show the magnetron in its customary position. In Fig. 1, numeral 10 designates the magnetron cavity resonator. Numeral 11 designates a tuning mechanism which provides relative movement of the end closures of cavity resonator 10. Two anode cooling coils 12 are disposed above and below cavity resonator 10. An output loop assembly 13 is coupled into the interior of the magnetron cavity resonator 10 and serves as the radio frequency output line. Numeral 14 designates the cathode-pole piece assembly, through which passes the coaxial heater lead from a bayonet plug 15 to the cathode structure within the magnetron cavity resonator 10. The bayonet plug 15 serves as the external connection for the heater and cathode. A pump lead 16 is connected to the interior of cavity resonator 10 in order to evacuate the magnetron. Two pole piece connections 17 are adapted to receive the opposite ends of the magnetic field excitation unit, not shown.

Fig. 2A shows a cross sectional view of the output assembly 13 of Fig. 1 drawn to a slightly enlarged scale. A tapered outer conductor 20 and tapered inner conductor 21 are electrically connected by a coupling loop 22 within the magnetron cavity resonator 10. The tapered outer conductor 20 may be made by die stamping a copper disc. The magnetron vacuum is maintained by a glass seal 23 which is joined to inner and outer coaxial nickel-cobalt tubes 24 and 25.

Although nickel-cobalt to glass seals are indicated throughout this specification, it is to be understood that alternative glass to metal seals may be used, if desired. Similarly any satisfactory equivalent for electrical insulation and vacuum sealing may be utilized, if desired.

Fig. 2B shows a partially cross sectional view taken through the axis of Fig. 1 and drawn to an enlarged scale. The magnetron structure within cavity resonator 10, the tuner mechanism 11 and the cathode-pole piece assembly 14 are shown in some detail. The cavity resonator 10 is formed by a cavity resonator shell 30 of substantially cylindrical construction and continuous with the rigid end closure of the cavity resonator. A circular diaphragm 31, not cross sectioned, constitutes the flexible end closure of cavity resonator 10. The cavity shell 30 may be drawn from a sheet monel disc; the diaphragm 31 may be die stamped from a sheet monel disc. Within the cavity resonator 10 is a "squirrel cage" or ring of interleaving anode fingers 32 and 33 which are arranged circumferentially about the magnetron axis with substantially uniform spacing between fingers. Alternate anode fingers 32 at one end thereof are connected to, or integral with, the upper annular anode section 34, while the other anode fingers 33 at one end thereof are connected to, or integral with, the lower annular anode section 35. Thus anode section 34 and anode fingers 32 may be said to constitute the upper anode while anode section 35 and anode fingers 33 may be said to constitute the lower anode. These are the basic squirrel cage anodes. Various improved anode structures, which involve slight modifica-

tions of these basic anodes, have been developed to improve the efficiency of the magnetron. The anodes generally may be milled from copper rod.

The annular anode section 34 passes through and is soldered to diaphragm 31, while annular anode section 35 passes through and is soldered to the rigid end closure portion of cavity resonator shell 30.

The term "soldered" indicates a process for affixing two or more metallic members with a good electrical connection therebetween. The soldered junction may be intended primarily as a vacuum seal between the metallic members. Silver solder is commonly used in magnetron work. Gold solder is preferable where a vacuum seal soldered junction including nickel-cobalt is to be made. It is to be understood that any equivalent process may be substituted for the soldering, if desired.

20 A tuner yoke 36 having substantially the same shape and construction as the cavity shell 30 is soldered atop the junction of diaphragm 31 and cavity shell 30, thereby being rigidly fixed with respect to the cavity shell 30. The annular anode sections 34 and 35 are grooved on their outer circumferences to simplify the support of the anode cooling coils 12 in the cavity-anode assembly and in the completed magnetron.

25 Centrally disposed within the tuner mechanism 11 is one of the two magnetic pole pieces, the upper or tuner pole piece 37, not cross sectioned. The face of pole piece 37 projects slightly below the upper edge of the upper annular anode section 34, and is soldered thereto. The upper end of pole piece 37 is threaded. The tuner pole piece 37 is movable with respect to a tuning yoke extension 38, the tuning yoke extension 38 being rigidly affixed to tuning yoke 36 by a number of yoke screws 39, not cross sectioned. Hence relative axial motion of the tuner pole piece with respect to the tuning yoke extension 38 results in relative axial motion between the two annular anode sections and their respective anode fingers. The motion of the tuner pole piece 37 is effected by a tuning adjustment nut 40 operating upon the threaded end of tuner pole piece 37 and moving with respect to the yoke extension 38 upon ball bearings 41. Pressure against pole piece 37 is maintained by a spring 42 the tension of which may be adjusted by a tension nut 43. Pole piece 37 maintains pressure against spring 42 by means of a stop washer 44. A shim washer 45 limits the upward motion of the tuner pole piece 37 and hence the maximum separation between the anodes. Another shim washer 46 limits the closest approach of the anode fingers to the bottom of their respective slots and prevents the anode fingers from butting against the opposite anode section and possibly buckling.

30 The cathode-pole piece assembly 14 is shown partially cross sectioned. Numeral 47 designates the cathode, not cross sectioned, within which is the heater element, not shown. Two radially enlarged sections 48 on cathode 47 are employed in the usual fashion to confine the electron beam. A face of the cathode pole piece designated by numeral 49 projects slightly inside anode section 35. Pole piece face 49 is opposite the face of the tuner pole piece 37 so that a magnetic field between the two faces is maintained parallel to the magnetron axis in the usual fashion. The cathode-pole piece assembly 14 is soldered to the annular anode section 35 around the circumference and at the juncture between pole piece face 49 and anode section 35. The cathode and heater

are supplied by the bayonet plug 15, having a central terminal 50 continuous with the inner conductor of the coaxial heater lead. The outer terminal of the bayonet plug 15 is designated by numeral 51 and is connected by a wire 51a to outer conductor 52 of the coaxial heater lead. Outer terminal 51 and outer conductor 52 are also the cathode connection, the cathode being connected to one side of the heater. A vacuum seal 53 extends between a nickel-cobalt tube 54 and the terminal 51 and serves to insulate terminal 51 from the main metallic surface of the magnetron. The inner and outer terminals of bayonet base 15 are insulated by an insulating bead 55. A glass bead 56 serves to insulate and support inner conductor 50 from outer conductor 52, and also as a vacuum seal.

Fig. 3 shows the several magnetron components and the jigs used in the cavity-anode assembly. An upper jig holds the tuning yoke 36, the tuner pole piece 37, and the upper annular anode section 34, in axial alignment. A lower jig 61, resting in a support 62, holds the cavity shell 30, the lower annular anode section 35, the diaphragm 31 and the upper annular anode section 34 in axial alignment. This maintains the axial alignment which is necessary for the cavity-anode assembly. The jigs 60 and 61 may be oxidized stainless steel to prevent their being soldered to the assembly.

The upper and lower anodes are shown isometrically in Fig. 3. Annular anode sections 34 and 35 and their respective anode fingers 32 and 33 are the basic squirrel cage anodes.

Various improved anode structures which involve rearrangements of the anode fingers or special tuning means may be used, if desired. Thus for example, the efficiency may be improved by using phase-reversing anode fingers; in one form of phase-reversing finger, the adjacent fingers in two diametrically opposite pairs of fingers are connected to the same anode section, the remainder of the fingers being rearranged to be alternately connected to opposite anode sections; in another form of phase-reversing fingers, each of the aforementioned pairs of fingers is replaced by a single wide anode finger. As further examples, various anode structures for extending the tuning range, or for securing a desired shape of tuning curve, or for decreasing moding of the magnetron, have been devised. Accordingly the invention is not limited to the anode structure shown.

Referring in Fig. 3 to the drawing of the cavity shell 30, numeral 63 designates an output hole.

Fig. 4A is a simplified isometric view showing the magnetron components for the anode-cavity assembly assembled on the upper and lower jigs 60 and 61, and supported on the support 62. A spacing tool 64 is inserted in the output hole 63 in order to accurately adjust the spacing between two adjacent anode fingers. The action of this spacing tool is illustrated in Fig. 4B.

An illustration of the alignment of the components and the position of the solder prior to soldering the cavity-anode assembly is shown in Fig. 5. As herein described, wire solder, generally silver or gold solder, may be used. However the actual method of making the junctions is not intended to limit the applicability of the invention. Where the solder may be held in position by gravity, as at 65, the wire solder is merely placed around the junction to be soldered. When this cannot be done, as at point 66, the solder is spot welded into place at several points.

Fig. 6 shows one possible method of disposing a heating wire to effect the soldering in the cavity-anode assembly. A molybdenum wire 67, fed by an external source, is used to heat the parts to soldering temperature. The entire assembly of Fig. 6 is enclosed in a hydrogen atmosphere to serve as a flux for the solder and to prevent the formation of oxides which is in accordance with standard practice in the vacuum tube industry. The method of heating described is of course optional and high frequency induction heating or any other method of affixing the parts may be used.

After the completion of the cavity-anode assembly as described above, the remaining components are attached to the magnetron. The output assembly 13 is assembled separately and the cathode-pole piece assembly 14 is likewise assembled separately. These two assemblies may be attached to the cavity-anode assembly by much the same procedure as that outlined for soldering the cavity-anode assembly. The tuner assembly 11 is not a part of the vacuum system and is removable for adjustment. It is attached to the remaining structure after the assembly is completed. The evacuation and degassing of the magnetron are accomplished in the usual fashion.

The use of the jigs in the assembly and the design of the magnetron components result in a great simplification of the manufacturing process. Tolerances have been reduced and practically all of the magnetron components except the anodes require little or no machining, and may be largely formed or die stamped. The practically all-metallic construction of the magnetron is most advantageous.

It is obvious that there may be deviations from the invention as described which still fall fairly within the spirit and scope of the invention.

Accordingly all such deviations are claimed which fall fairly within the spirit and scope of the invention as identified in the hereinafter appended claims.

What is claimed is:

- 45 1. A squirrel cage magnetron including a cylindrical cathode and a substantially cylindrical cavity resonator coaxial with said cathode, two annular anode sections disposed coaxially with said resonator and connected to opposite end closures of said resonator, a ring of interleaving anode fingers mounted circumferentially about the axis of and within said resonator and entirely between said anode sections, adjacent fingers being connected at one end thereof to opposite annular anode sections, means including magnetic pole pieces at opposite ends of said cavity resonator and each affixed to one of said anode sections for generating a magnetic field substantially parallel to the axis of said resonator, one 55 of said pole pieces being fixed to said resonator and the other pole piece being adjustably mounted on said resonator and means mounted on said resonator and connected to said other pole piece for moving one of said anode sections and said other pole piece axially with respect to the other anode section and said one pole piece.
- 55 2. A squirrel cage magnetron as defined in claim 1 in which one of said end closures of said resonator has a flexible portion, and means connected to said last-named end closure for moving it and its attached fingers axially with respect to the other end closure of said resonator.
- 60 3. A squirrel cage magnetron as set forth in claim 1 in which said cavity resonator has a flexible end closure and in which said means for mov-

ing said anode section and pole piece includes a yoke rigidly affixed to said cavity resonator, said movable pole piece extending axially through said yoke, and means connected to said pole piece for moving said pole piece with respect to said yoke.

4. A squirrel cage magnetron including a cylindrical cathode and a substantially cylindrical cavity resonator coaxial with said cathode, two annular anode sections disposed coaxially with said resonator and connected to opposite end closures of said resonator, said anode sections having circumferential grooves on the outer peripheries thereof, one of said end closures being flexible, a ring of interleaving anode fingers mounted circumferentially about the axis of and within said resonator and entirely between said anode sections, adjacent fingers being connected at one end thereof to opposite annular anode sections, means including a pair of magnetic pole pieces at opposite ends of said cavity resonator and each affixed to one of said anode sections for generating a magnetic field substantially parallel to the axis of said resonator, means mounted on said resonator for moving one of said anode sections and the pole piece affixed thereto axially with respect to the other anode section and the other pole piece, said last named means including a yoke rigidly affixed to said cavity resonator, the movable pole piece extending axially through said yoke, and means for moving said movable pole piece with respect to said yoke, and anode cooling coils disposed around said circumferential grooves.

5. A magnetron comprising aligned first and second like, hollow, conductive cylinders having open and closed ends, said open ends facing one another, a single circular, flexible conductive diaphragm fastened across said open ends and interconnecting said cylinders, the closed ends of said members and said diaphragm each having a central aperture therein, two opposing annular anode sections disposed concentrically within said cylinders, the first of said sections being mounted within the aperture of said flexible diaphragm and fastened thereto and the second of said sections being mounted within the aperture in the closed end of said first cylinder and fastened thereto, a ring of interleaving anode fingers disposed concentrically within said cylinders, adjacent fingers being connected at one end thereof to opposite annular sections, a cathode disposed concentrically within said ring of fingers, and means connected to said first section

for moving said first section axially of said cylinders to effect the tuning of said magnetron.

6. A magnetron as claimed in claim 5, in which said last-named means comprise a third hollow, conductive cylinder concentric with the axis of said first and second cylinders, and of smaller diameter than said first and second cylinders, said third cylinder being without the structure formed by said first and second cylinders and said diaphragm, said third cylinder being mounted at one end thereof to said second cylinder at the closed end thereof, whereby the central aperture in the closed end of said second cylinder is aligned with the hollow portion of said cylinder, a piston within and concentric with said third cylinder fastened at one end to the first of said annular sections, and means connected to said piston for moving said piston axially of said third cylinder.

7. A magnetron as claimed in claim 6, wherein said piston is formed of ferro-magnetic material, and the end thereof fastened to said first annular section is expanded in the form of a first face plate across the opening in said first annular section, and further including a second face plate of ferro-magnetic material fastened to said second annular anode section across the opening therein, said second face plate including a central aperture therein to allow the passage therethrough of said cathode.
